OHIO; SAID COLLEY AND SAID SOPER ASSIGNEES TO SAID LAW

SWIVEL SEAT

Application filed August 19, 1927, Serial No. 214,080. Renewed April 4, 1931.

This invention relates to furniture and more particularly to a chair or seat adapted to support a person and which is connected to a table or desk in such a manner as to be pivotally swung towards or away therefrom, as the case may be.

It is an object of the present invention to provide a swinging seat adapted to be swung under a desk out of the way and at the same time lock the seat in such a manner as to prevent it coming in contact with any portion of the desk so as to damage the latter.

Another object of the invention is to provide a partially oscillating seat pivotally connected to the leg of a desk or other supporting structure which, when in its normal inward position under the desk, is prevented from oscillating, but when in its normal outward position is permitted to oscillate through a limited arc but not sufficient to permit the back of the seat to engage and injure the desk or other supporting structure.

Another object of the invention is to provide a seat, of the type referred to, which when in its normal outward position can be moved to its normal inward position beneath the desk or supporting structure and be automatically oscillated to properly position the seat beneath the desk and to maintain the same in proper position thereunder so that the seat cannot be oscillated thereby preventing injury to the desk or supporting structure.

Heretofore, pivoted seats have been provided and employed in connection with counters, desks and other supporting structures, but the seat is of the customary type without a back rest so that the seat can be oscillated without interference with the supporting structure, but where backs have been employed in connection with the pivoted seats, these backs engage with the supporting structure when the seat is swung about its pivot which usually results in marring the supporting structure. These seats are furthermore usually supported by the floor and as the pivotal movement of the seat is limited by the engagement of the back with the supporting structure, it is usually very inconvenient for the occupant to mount these seats

because of the restricted pivotal movement thereof. With the present structure and arrangement, applicant has avoided this objection by providing a seat having a supporting back which is pivotally connected to the leg of the desk or other supporting structure, the seat of which is further mounted for a predetermined oscillatory movement independently of its pivot connection so that the seat can be swung about its pivot away from the desk and then the seat oscillated independently which permits the occupant to leave the seat without interference by the desk or supporting structure. This arrangement further permits the occupant to also properly position himself with respect to the desk or other supporting structure to suit his own conditions, inasmuch as it is the desire of some persons to be positioned close to the desk while others desire to be positioned farther away from the desk.

With the objects above indicated and other objects hereinafter explained in view, my invention consists of the construction and elements hereinafter described and claimed.

In the drawings, Fig. 1 shows a side elevational view of the seat in its normal inward position beneath the desk or supporting structure which is indicated by dotted lines;

Fig. 2 is a rear elevational view of the seat showing its connection with the desk or supporting structure but with the seat swung outwardly about its pivot;

Fig. 3 is a plan view of the operating mechanism for the seat showing its connection with the leg of the desk, the full lines representing the seat in its normal outward position while the dotted lines represent the seat in its normal position;

Fig. 4 is a fragmentary perspective view of the operating mechanism for the seat;

Fig. 5 is a vertical view partly in section showing the manner of supporting the seat to permit its oscillation about its vertical axis; and

Fig. 6 is a plan view of the seat support showing the reversible feature of the bracket for the stop pin.

In the drawings, 10 represents a desk or other supporting structure having a plural-

ity of depending legs 11 which are suitably supported by a floor or other structure. The seat is indicated at 12 and has a back portion 13 connected to the seat by means of a 5 pair of resilient braces 14 which are bolted or otherwise secured respectively to the seat and back portions. This seat is adapted to be swung beneath the desk when the same is not being used and to be swung outwardly 10 from beneath the desk when it is desired to be occupied, and the operating mechanism for the seat, which will be hereinafter more fully described, prevents engagement between the back portion 13 and the desk 10 15 while the seat is being moved, thereby preventing damage or marring of the desk.

The seat 12 is provided on its under surface with a casting 15 which is bolted or otherwise secured thereto, and has extending 20 downwardly therefrom a seat post or stud 16.

The seat 12 is supported in a horizontal position by a bracket which comprises a spider 17 having at one side a cylindrical integral leg or support 18, the lower end of 25 which extends below the spider 17 and has bifurcated ends 19 between which is rotatably supported a rubber tire wheel or caster 20 adapted to engage and be moved upon the floor. The upper end of the leg 18 is provided with a central bore 21 of a diameter sufficient to rotatably receive therein the stud 16 of the seat 12. A thrust ball 22 is positioned at the end of the bore 21 and is adapted to be engaged by the end of the stud 20 30 to thereby permit the stud 16 carrying the seat 12 to be more freely oscillated about its axis. The bore 21 is provided with a pair of counterbores 23 slightly larger than the diameter of the stud 16 and adapted to retain a quantity of oil introduced therein for the 35 purpose of lubricating the stud 16.

The end of the spider 17 opposite the cylindrical support 18 is provided with a pair of 40 extensions or lugs 24 horizontally spaced apart and provided with apertures adapted to suitably receive therein a vertical pin or rod 25 about which the bracket is pivoted. These lugs or extensions 24 are positioned 45 between a pair of lugs 26 extending outwardly and formed integral with a triangular shaped bracket 27 bolted or otherwise secured to one of the legs 11 of the desk 10, the upper and lower ends of the pin 25 being 50 suitably mounted in the lugs 26 so that the spider 17 is permitted to pivot about the pin 25 when the seat is moved under or away from the desk. It will be noted from the construction 55 so far described that the weight of the occupant seated upon the seat is carried entirely by the cylindrical leg 18 thereby eliminating any load upon the connection between the leg of the desk 10 and the spider 17, this connection functioning entirely as a pivot 60 about which the seat 12 is swung.

When the seat 12 is in its normal inward position, as shown in Fig. 1, it will be noted that the back 13 is adjacent the top of the desk 10 and it is desirable to prevent engagement or interference between the back and the desk to thereby prevent marring or injury of the desk. It is, therefore, advisable to provide a means for preventing the seat 12 from oscillatory movement about the stud 16 and this is accomplished in the following manner. The cylindrical leg 18 is provided with a lateral extension 28 formed integral with the upper portion of the leg and is adapted to engage with a depending pin or stop 29 secured in the lower portion of the casting 15 upon the underside of the seat 12. A lever or arm 30, as shown in Fig. 4, is provided with a substantially centrally located aperture 31 adapted to be freely mounted upon the stud 16 between the upper portion of the cylindrical leg 18 and the underside of the casting 15. This lever is provided with an extension 32 adapted to extend forwardly and into the path of movement of the depending pin or stop 29, as clearly shown in Fig. 3, so as to prevent oscillation of the seat 12 beyond a certain point. The opposite end of the lever 30 is bifurcated, as at 33, and is pivotally connected by a pin 34 to one end of a link 35 while the opposite end of the link is pivotally connected by a pin 36 between the bifurcated ends 37 of an extension 38 extending outwardly and formed integral with the upper portion of the triangularly shaped bracket 27. This linkage mechanism, just described, is of such a nature that the lever or arm 30 has a straight line motion which inasmuch as the depending pin or stop 29 engages with the end 32, prevents oscillation of the seat 12 in a counter-clockwise direction whether in its normal position beneath the desk or in its outward position.

When the seat 12 is in its normal inward position beneath the desk, as indicated by dotted lines in Fig. 3, it will be seen that the depending pin or stop 29 is maintained between the end 32 of the link 30 and the extension 28 of the cylindrical leg 18 so that the seat 12 is prevented from any oscillatory movement about its vertical axis, the back 13 being prevented thereby from engagement with the desk 10.

When the seat is moved to its normal outward position, as indicated in full lines in Fig. 3, the end 32 of the link 30 and the extension 28 of the cylindrical leg 18 have been moved away from each other and the depending pin or stop 29 is, therefore, in engagement with only the extension 32. The seat is, therefore, prevented from rotation about its vertical axis in a counter-clockwise direction by the engagement between the extension 32 and the pin 29 but is permitted to be moved in a clockwise direction about its vertical axis until the pin or stop 29 is

moved to the position indicated in dotted lines, at which time it engages with the extension 28 and is prevented from further movement in that direction. However, when

5 the pin or stop 29 is in such engagement, the seat 12 has been oscillated about its vertical axis through an arc of substantially 90 degrees which thereby permits the occupant to either leave or seat himself upon the seat

10 12 without interference by the desk.

When the seat 12 is in its normal outward position and the seat has been oscillated in a clockwise direction until the stop 29 is in engagement with extension 28, the seat can

15 be returned to its normal inward position without occupancy by merely pushing the seat inwardly. The seat being pivoted upon the pin 25 will move inwardly and the engagement between the extension 28 and the

20 pin 29 will cause the seat to be oscillated about its vertical axis throughout its movement until the pin 29 is again retained between the extension 32 and the extension 28. During this time the back 13 has been moved

25 from a position at right angles to the front edge of the desk to a position substantially parallel with the front edge of the desk 10 and the back has been prevented from being moved into engagement with the desk 10.

30 It might be stated that independently of the position of the seat 12 between its normal inward position and its normal outward position the seat 12 cannot be oscillated about its vertical axis to bring the back 13 into engagement with any portion of the desk 10,

35 thereby preventing any injury or marring of the desk.

Further, it should be understood that this seat can be attached opposite to that shown 40 in the drawings so that the seat can be swung in the opposite direction as already described, it being only necessary to change the bracket 27 from a left-hand bracket, as shown, to a right-hand bracket, reversing the position of the lever 30 and changing the position of the depending pin from that shown in the drawings to the opening 39 provided upon the under face of the casing 15.

While I have described the preferred construction and arrangement of the seat embodying the present invention, it is to be understood that modifications and changes may be resorted to without departing from the spirit of the invention as defined in the 55 appended claims.

Having thus described my invention, I claim:

1. The combination with a desk or the like, of a seat, means for connecting said seat to the desk in such a manner that said seat is adapted to be swung under or away from said desk, said means including a pivot for the seat located below the seat within the confines thereof, and means associated with

60 65 said first named means for decreasing the

oscillatory movement of said seat about its pivot as it is moved to a position beneath said desk.

2. The combination with a desk or the like, 70 of a seat, means for connecting said seat to the desk in such a manner that said seat is adapted to be swung under or away from said desk, said means including a pivot for the seat located below the seat within the confines thereof, and means associated with said first named means for decreasing the oscillation of said seat about its pivot as it is moved to a position beneath the desk, said last named means being withdrawn sufficiently to permit increasing oscillation when the seat is moved away from said desk.

3. The combination with a desk or the like, 75 of a pivoted seat, a support for said seat, means for pivotally connecting said support to said desk to thereby permit said seat to be moved beneath or away from said desk, and means carried by said first named means for preventing oscillation of said seat about its axis as it is moved to a position beneath said desk.

4. The combination with a desk or the like, 80 of a pivoted seat, a support for said seat, means for pivotally connecting said support to said desk to thereby permit said seat to be moved beneath or away from said desk, and means carried by said support and actuated by movement of said seat for preventing oscillation of the seat about its pivot as the seat is moved to a position beneath said desk, said last named means being moved partially out of operative position when the seat is swung away from said desk.

5. The combination with a desk or the like, 85 of a pivoted seat, a support for said seat, means for pivotally connecting said support to said desk to thereby permit said seat to be moved beneath or away from said desk, and means for increasing the possible oscillatory movement of said seat about its axis proportionately as it is moved to a position away from said desk.

6. The combination with a desk or the like, 90 of a pivoted seat, a support for said seat, means for pivotally connecting said support to said desk to thereby permit said seat to be moved beneath or away from said desk, and means carried by said support for automatically preventing oscillatory movement of said seat about its axis as it is moved into position beneath said desk.

7. The combination with a desk or the like, 95 of an oscillatory seat, a support for said seat, means for pivotally connecting said support to the desk so that said seat may be moved into position beneath or away from said desk, a roller mounted on said support and adapted to engage a floor, and means for preventing oscillation of said seat about its axis as it is moved into position beneath said desk, said

means being withdrawn partially as the seat is moved to a position away from the desk.

8. The combination with a desk or the like, of an oscillatory seat, a support for said seat, means for pivotally connecting said support to the desk so that said seat can be moved into position beneath or away from said desk, a member mounted upon said support about the axis of said seat, means for controlling the movement of said member, a depending pin carried by said seat adapted to engage said member, and an extension on said support also adapted to engage said pin, the latter being secured between said member and extension when said seat is positioned beneath said desk to thereby prevent oscillation of said seat about its axis.

9. The combination with a desk or the like, of an oscillatory seat, a support for said seat, means for pivotally connecting said support to the desk so that said seat can be moved into position beneath or away from said desk, a member mounted upon said support about the axis of said seat, means for controlling the movement of said member, a depending pin carried by said seat adapted to engage said member, and an extension on said support also adapted to engage said pin, the latter being secured between said member and extension when said seat is positioned beneath said desk to thereby prevent oscillation of said seat about its axis.

10. The combination with a desk or the like, of a seat, a back connected to said seat, a support in which said seat is pivotally mounted, a bracket adapted to be secured to the desk, said support having a portion which is pivotally connected to said bracket to thereby permit said seat to be moved into position under or away from said desk, a pivoted arm mounted about the axis of said seat and connected to said bracket, an extension carried by said support, and a depending pin secured to said seat and disposed between said arm and said extension, said arm and extension being moved into engagement with said pin as said seat is moved into position beneath said desk to prevent oscillation of said seat about its axis and being moved out of engagement with said pin as said seat is moved into a position away from said desk to permit oscillation of said seat about its axis.

11. An article of furniture as described comprising an oscillatory seat, a support for said seat, a bracket adapted to be connected to a desk and having a pivotal connection with said support, and means for securing said seat against oscillation about its axis as it is moved to one position, said means being withdrawn as the seat is moved to another position.

12. An article of furniture as described

comprising an oscillatory seat, a support for said seat, a bracket adapted to be connected to a desk and having a pivotal connection with said support, and means for securing said seat against oscillation about its axis as it is moved to one position, said means being withdrawn sufficiently to permit partial oscillation as the seat is moved to another position.

13. An article of furniture as described comprising an oscillatory seat having a back portion, a supporting leg on which said seat is mounted and provided with a roller at its lower end, a bracket adapted to be connected to a desk or other structure, said leg having a portion pivotally connected to said bracket to thereby permit said seat to be moved about said pivot, an arm mounted upon said leg about the axis of said seat and having a connection with said bracket, an extension at the upper portion of said leg, and a depending member on the bottom of said seat disposed between said arm and extension, said depending member being securely maintained between said extension and arm when said seat is moved in one direction to thereby prevent oscillation of the latter about its axis, and released when said seat is moved in the opposite direction to thereby permit limited oscillation about its axis.

14. In a seat construction, a seat mounted to oscillate about an axis within itself, means for supporting said seat adapted to oscillate about a different axis, and means for preventing oscillation of said seat about its axis as said supporting means is moved to one position, said last named means being rendered ineffective as said supporting means is moved to another position.

In testimony whereof, we hereunto affix our signatures.
